US00D786279S

(12) **United States Design Patent** (10) Patent No.: **US D786,279 S**
McKim et al. (45) Date of Patent: **** May 9, 2017**

(54) **DISPLAY SCREEN WITH GRAPHICAL USER INTERFACE FOR A VISCOMETER OR RHEOMETER**

(71) Applicants: **Teresa L. McKim**, Abington, MA (US); **James A. Salomon**, Providence, RI (US); **Alex H. Mak**, Canton, MA (US); **Robert P. Bishop**, Pembroke, MA (US); **Charles J. Falzarano**, Lakeville, MA (US)

(72) Inventors: **Teresa L. McKim**, Abington, MA (US); **James A. Salomon**, Providence, RI (US); **Alex H. Mak**, Canton, MA (US); **Robert P. Bishop**, Pembroke, MA (US); **Charles J. Falzarano**, Lakeville, MA (US)

(73) Assignee: **Brookfield Engineering Laboratories, Inc.**, Middleboro, MA (US)

(**) Term: **14 Years**

(21) Appl. No.: **29/449,803**

(22) Filed: **Mar. 15, 2013**

(51) LOC (10) Cl. **14-04**

(52) U.S. Cl.

USPC **D14/486**

(58) Field of Classification Search

USPC **D14/485-495**

(57) **CLAIM**

The ornamental design for display screen with graphical user interface for a viscometer or rheometer, as shown and described.

DESCRIPTION

THE FIGURE is a front view of a display screen with graphical user interface for a viscometer or rheometer showing our new design.

The broken line showing a display screen forms no part of the claimed design.
